UNITED STATES PATENT OFFICE.

CLAUDE GEORGE SONGY AND PRUDENT GERARD SONGY, OF WALLACE, LOUISIANA.

SULPHUR MACHINE.

Application filed April 16, 1927. Serial No. 184,348.

My invention relates to improvements in apparatus for bleaching saccharine solutions of various kinds and more especially intended for use with raw juice either from the sugar cane or from the sugar beet, and it is intended to provide apparatus, which will effect efficient bleaching with a minimum quantity of SO_2 derived from the burning of sulphur in air.

Where an excess of SO_2 is used, an acid reaction follows, which it is necessary to correct by an alkaline reagent, and it is especially desirable to effect the bleaching with as small a quantity of sulphur fumes as possible.

In order to effect this, it is especially desirable to have the sulphur fumes thrown into intimate contact with the liquid to be bleached.

Moreover, in order to secure better results, it is desirable to have the gases containing the sulphur fumes admitted in a comparatively cool state, instead of direct from the sulphur furnace. In such cool state, the initial action is less active and the sulphur fumes can be more evenly distributed through the liquid than where the gases are applied in a hot state. Moreover, by diminishing the quantity of sulphur fumes added to the juice, before liming, the juice may be settled in ordinary tanks, and the impurities removed without material loss due to acidifying or like causes.

In order to accomplish the foregoing and other results, I have devised an apparatus, which will be more clearly understood after reference to the accompanying drawings, in which like parts are indicated by similar reference symbols throughout the several views, and in which:

Figure 1 is a diagrammatic view of the apparatus, the sulphur box being shown in vertical section along the line 1—1 of Figure 2, and looking in the direction of the arrows;

Figure 2 shows a vertical section through the sulphur box along the line 2—2 of Figure 1, and looking in the direction of the arrows, parts being shown in elevation;

Figure 3 shows a horizontal section along the line 3—3 of Figures 1 and 2, and looking down; and

Figure 4 shows a horizontal section along the line 4—4 of Figures 1 and 2, and looking down.

A represents the furnace, in which the sulphur is burned in air, which is shown diagrammatically in Figs. 1 and 3, the fumes from the furnace consisting mainly of nitrogen and SO_2 escape from the furnace A through the pipe B, which pipe passes through the cooling tank C supplied with cooling fluid, such as water, through the pipe D, which water is carried off through the pipe E. After passing through the cooling medium, the pipe B delivers the products of combustion of the sulphur furnace to the sulphur box F, where the sulphitation is accomplished. The flow of the products of combustion may be controlled by any suitable valve arrangement b. The sulphur box F is in the form of a closed rectangular chamber, which may be made of wood or other suitable material and is provided with a chimney G at the top thereof of any desired height, into which a steam jet is supplied through the pipe H controlled by the valve h, thus causing a suction in the interior of the chamber, tending to draw the products of combustion from the furnace A upwards. The liquid to be bleached is supplied through the pipe I and the treated liquid is carried off through the pipe J controlled by the valve j, to the settling tanks, one of which is shown in part at J'. To prevent the escape of sulphur fumes into the factory when the sulphur box is empty of liquids, the pipe J is bent to form a liquid seal.

In the interior of the sulphur box near the top thereof, we provide a screen K, so arranged as to separate the liquid into small streams or a spray, which falls down in the sulphur box, part of said liquid falling on the inclined deflector L and part directly on the paddle wheel M, having a series of radial blades m, the said wheel being mounted on a shaft N, which is caused to rotate in the direction indicated by the arrow in Fig.

1. The deflector L will throw the liquid falling on the same on to the paddle wheel, thus thoroughly mixing the same with the products of combustion from the furnace, which are constantly rising upward in the sulphur box. After the liquid passes the upper paddle wheel M, I may provide another inclined deflector L', which directs the liquid on to a lower paddle wheel M', mounted on a shaft N', which is driven in the direction of the arrow, as shown in Fig. 110

1, and thus further intimate association of the liquid with the products of combustion rising upward is secured. A third deflector L^2 may be provided to screen the outlet b^o 5 of the pipe B, and this outlet is placed high enough from the bottom of the sulphur box to prevent the liquid accumulating in the bottom of said box from finding its way into the pipe B and flowing back to the furnace A.

The paddle wheels M and M' may be rotated in any convenient way, as by the belt O and pulley P driving the shaft N'; on which the shaft or pulley Q is mounted, 15 which carries the cross-belt R, driving the pulley S on the shaft N, or any other convenient way of driving these paddle wheels may be adopted, as desired.

By having the products of combustion enter the sulphur box in the cool condition, the reaction will not be so vigorous as if the gases were applied hot, and consequently these gases will flow up through the sulphur box and will have an opportunity to be intimately mixed with the downward descending liquid, and thus a more uniform sulphitation will be secured, and the gases escaping from the chimney G will have very little, if any, traces of sulphur remaining 25 therein, but will be mostly inert nitrogen with small quantities of other gases associated therewith, which will not affect the sulphitation of the liquid.

By the herein described arrangement, a 30 very small quantity of sulphur fumes may be distributed uniformly through a large mass of liquid, and the slow reaction that results will enable the sulphitation to be uniform and sufficiently complete for practical purposes, using only a very small quantity of sulphur.

The draft for the gases flowing through the apparatus may be controlled by the valve h and steam jet H.

Having thus described my invention, what I claim and desire to secure by Letters Patent of the United States is:

1. Apparatus for bleaching saccharine solutions comprising a furnace adapted to burn sulphur in air, a pipe carrying off the products of combustion from said furnace, a cooling tank surrounding a portion of said pipe, means for supplying cooling medium to said tank, a rectangular box stood on end and receiving in its lower portion the cooled gases from said furnace, means for carrying off the spent gases from the top of said box, means for supplying the liquid to be bleached to the upper portion of said box 50 and for drawing it off from the lower portion thereof, a series of downwardly inclined baffle plates or shelves arranged transversely of said box and extending across one side only thereof, and paddle wheels located beneath the liquid falling from said deflecting plates, with means for rotating said paddle wheel against the action of the falling liquid.

2. Apparatus for bleaching saccharine solutions comprising a furnace adapted to burn sulphur in air, a pipe carrying off the products of combustion from said furnace, a rectangular box stood on end and receiving in its lower portion the cooled gases from said furnace, means for carrying off the spent 70 gases from the top of said box, means for supplying the liquid to be bleached to the upper portion of said box and for drawing it off from the lower portion thereof, a series of downwardly inclined baffle plates or shelves arranged transversely of said box and extending across one side only thereof, and paddle wheels located beneath the liquid falling from said deflecting plates, with means for rotating said paddle wheel against the action of the falling liquid.

2. Apparatus for bleaching saccharine solutions comprising a furnace adapted to burn sulphur in air, a pipe carrying off the products of combustion from said furnace, a rectangular box stood on end and receiving in its lower portion the cooled gases from said furnace, means for carrying off the spent 75 gases from the top of said box, means for supplying the liquid to be bleached to the upper portion of said box and for drawing it off from the lower portion thereof, a series of downwardly inclined baffle plates or shelves arranged transversely of said box and extending across one side only thereof, and paddle wheels located beneath the liquid falling from said deflecting plates, with means for rotating said paddle wheel against the action of the falling liquid.

3. Apparatus for bleaching saccharine solutions comprising a furnace adapted to burn sulphur in air, a pipe carrying off the products of combustion from said furnace, a cooling tank surrounding a portion of said pipe, means for supplying cooling medium to said tank, a rectangular box stood on end and receiving in its lower portion the cooled gases from said furnace, a chimney and a steam jet for carrying off the spent gases from the top of said box, means for supplying the liquid to be bleached to the upper portion of said box and for drawing it off from the lower portion thereof, a screen across the upper portion of said box, a series of downwardly inclined baffle plates or shelves arranged transversely of said box and extending across one side only thereof, and paddle wheels located beneath the liquid falling from said deflecting plates, with means for rotating said paddle wheel against the action of the falling liquid.

4. Apparatus for bleaching saccharine solutions comprising a furnace adapted to burn sulphur in air, a pipe carrying off the products of combustion from said furnace, a cooling tank surrounding a portion of said pipe, means for supplying cooling medium to said tank, a rectangular box stood on end and receiving in its lower portion the cooled gases from said furnace, means for carrying off the spent gases from the top of said box, means for supplying the liquid to be bleached to the upper portion of said box and for drawing it off from the lower portion thereof, a downwardly inclined baffle plate or shelf arranged transversely of said box and extending across one side only thereof, and a paddle wheel located beneath the liquid falling from said deflecting plate, with means for rotating said paddle wheel against the action of the falling liquid.

5. Apparatus for bleaching saccharine solutions comprising a furnace adapted to

- burn sulphur in air, a pipe carrying off the products of combustion from said furnace, a rectangular box stood on end and receiving in its lower portion the cooled gases from said furnace, means for carrying off the spent gases from the top of said box, means for supplying the liquid to be bleached to the upper portion of said box and for drawing it off from the lower portion thereof, a downwardly inclined baffle plate or shelf arranged transversely of said box and extending across one side only thereof, and a paddle wheel located beneath the liquid falling from said deflecting plate, with means for rotating said paddle wheel against the action of the falling liquid.
- 5 10 15 20 25
6. In apparatus for bleaching saccharine solutions, a rectangular box stood on end and adapted to receive in its lower portion the cooled gases from said furnace, a chimney and steam jet for carrying off the spent gases from the top of said box, means for supplying the liquid to be bleached to the upper portion of said box and for drawing it off from the lower portion thereof, a
- screen across the upper portion of said box, a series of baffle plates or shelves arranged transversely of said box and each extending across one side only thereof, and paddle wheels located beneath the liquid falling from said deflecting plates, with means for rotating said paddle wheels against the action of the falling liquid.
- 30 35 40 45
7. In apparatus for bleaching saccharine solutions, a rectangular box stood on end and adapted to receive the gases from the sulphur furnace, means for carrying off the spent gases from the top of said box, means for supplying the liquid to be bleached to the upper portion of said box and for drawing it off from the lower portion thereof, a series of downwardly inclined baffle plates or shelves arranged transversely of said box and each extending across one side only thereof, and paddle wheels located beneath the liquid falling from said deflecting plates, with means for rotating said paddle wheels against the action of the falling liquid.
